RESISTANCE UNIT

John J. Mucher, Brooklyn, N. Y.

Application April 17, 1935, Serial No. 16,900

3 Claims. (Cl. 201—67)

This invention relates to resistance units, and has for an object to provide an improved construction wherein the parts are so formed and arranged that the breakable parts are so held as to prevent any accidental loose connections, the invention being an improvement over my co-pending application Serial No. 739,316, filed August 10, 1934.

Another object of the invention is to provide an improved construction wherein a continuous resistance element or a plurality of abutting resistance elements may be presented and formed of wire or other material with terminals taken therefrom at spaced points, the structure being such that the terminals are permanently connected with the resistance element.

An additional object of the invention is to provide an improved construction of resistance element wherein two or more elements may be arranged in abutting relation and terminals used at the ends of the combined structure and also to span the abutting ends in such a manner as to both electrically and mechanically connect said abutting ends.

25 In the accompanying drawing—

Figure 1 is a top plan view of a resistance unit disclosing an embodiment of the invention;

Fig. 2 is a longitudinal vertical sectional view through Fig. 1 approximately on the line 2—2;

30 Fig. 3 is a transverse sectional view through Fig. 1, approximately on the line 3—3;

Fig. 4 is an inverted perspective view of the casing shown in Fig. 1 before the sides have been collapsed;

35 Fig. 5 is a blank showing the protecting insulation illustrated in Fig. 2;

Fig. 6 is a top plan view of a resistance element disclosing an embodiment of the invention with the terminals arranged to fit into the blank shown in Fig. 5 and then be assembled into the casing as shown in Fig. 4;

Fig. 7 is a perspective view of one of the terminals shown in Fig. 6;

40 Fig. 8 is a view similar to Fig. 6 but showing three independent sections instead of two.

Referring to the accompanying drawing by numerals, 1 indicates a casing which is formed of metal and which has an apertured top 2, with sides 3 and 4 adapted to be bent around to form a bottom when the device is in operative position as shown in Fig. 2. The ends of the top 2 are bent down and then laterally to form apertured ears 5 and 6. This casing is adapted to receive a blank 7 which may be formed of asbestos or other insulating material and which when in operation

position will be as shown in Fig. 2. The blank 7 is adapted to be placed in the casing when the casing is arranged as shown in Fig. 4 so that the aperture 8 will be opposite the central aperture in the casing and the respective apertures 9 and 10 will be opposite the end apertures so that after the insulating blank 7 has been placed in the casing 1, a resistance unit 11, as shown in Fig. 6, may be placed in position with the terminal extensions 12, 13 and 14 extending through the apertures in the blank 7 and also the apertures in the casing 1 so that the parts will appear as shown in Fig. 1. The sides 3 and 4 are then bent over and pressed down tightly to pinch the various parts whereby all the parts 15 are held substantially against movement and also all the parts of the resistance member, as shown in Fig. 6, are protected against breakage or injury. The parts just described, except the resistance element and terminal shown in Fig. 6, are disclosed and claimed in the above-mentioned co-pending application, and, therefore, form no part of the present invention except in combination.

The structure shown in Figs. 6 to 8, inclusive, is new over the co-pending application above mentioned in that the various terminal units 12 to 14, inclusive, merge into bases 15, 16 and 17, and these bases each have turned-over ends 18 and 19, as shown in Fig. 7. The ends 18 and 19 are clinched in place so as to pinch the wire or other form of resistance used. In addition it will be noted from Fig. 6, that the resistance section 20 is independent of the resistance section 21. These elements while independent in construction abut. As shown, the elements are made of wire 35 but they could be made of other material without departing from the spirit of the invention. In elements of this kind it is quite often desirable that one section shall be of high resistance and the other of a comparatively low resistance and, 40 consequently, they are wound with wire having different resistances. As illustrated particularly in Fig. 6, the section 21 has a very high resistance, as, for instance, 5000 ohms, while the resistance of section 20 may be 30 ohms or 500 45 ohms, or some other number of ohms. It will be evident that the respective sections could present the same resistance, though ordinarily this would not be the case. Where the sections present the same resistance and are of the same 50 length one continuous winding of wire is preferable even though an intermediate terminal is used, but in most instances the different sections have widely different resistances and wattage dissipation and when originally manufactured are 55

wound at different times. The arrangement of the terminals presents comparatively wide bases so as to have good contact with the wire or other winding and in case of an intermediate terminal 5 base 16 there is an electrical connection between the two resistance sections and also a mechanical connection.

During the expansion and contraction of the entire unit, as shown in Fig. 2, there will never 10 be any loose motion or loose connection between the base 16 and the wires with which it is in engagement by reason of the fact that the base is firmly clinched in place and presents a very strong mechanical connection as well as electrical connection.

Under some circumstances it is desired to make more than just two sections as shown in Fig. 6.

In Fig. 8 this is illustrated by presenting three sections, though a greater number might be used 20 without departing from the spirit of the invention. In the showing of Fig. 8, the intermediate terminals 22 and 23 are formed as shown in Fig. 7, and being firmly clinched in place present good mechanical and electrical connections for the 25 various sections 24, 25 and 26. When using the structure shown in Fig. 6 with four terminals the casing 1 must be formed accordingly and also the insulation 7. When the structure shown in Fig. 6 is used the resistance unit may be utilized in 30 three different circuits, while when using the structure shown in Fig. 8 the same may be inserted into six different circuits and each circuit will have inserted therein a different resistance.

The resistance unit while being capable of use 35 in many places is particularly adapted for use in radio apparatus and usually the unit becomes heated while in use but is cooled when the apparatus is turned off. This heating and cooling naturally causes the metal in casing 1 to expand 40 and contract and also causes a certain action on the insulation 7. Where the various terminals are merely pressed against the insulating element, there will be a certain varying small amount of movement or shifting of these terminals as the 45 device expands and contracts, and this produces a very small amount of loose connection which results in noises and other objections as far as radio apparatus is concerned. By providing the clinched ends 18 and 19 as shown in Fig. 7, all 50 loose connections or all looseness caused in the device by expansion and contraction is eliminated. The expansion and contraction of the casing or any of the other parts will not in any way loosen or affect the electrical connection caused by the 55 pinching action of the bases of the respective terminals so that regardless of the heating and cooling of the device there will always be a good elec-

trical connection at every terminal and this condition will remain as long as the unit is usable. In effect the clamping or clinching of the bases of the terminals causes the same to be permanently connected with the resistance unit, and in effect substantially integral with the wires thereof so that a loose connection cannot take place at any time during the use of the device.

In the particular resistance illustrated in the drawing there is provided a base of insulating material and on this a resistance wire is wound. In the manufacture of this resistance element it is usually made in some considerable length and then cut off to the desired length when completing a finished product as shown in Figs. 1 and 2. 15

I claim:

1. In a resistance unit of the character described, a plurality of resistance elements arranged in a group end to end, each element having a base and a winding of resistance wire extending from substantially one end to the other said resistance elements abutting in actual alignment, a terminal positioned at the respective ends of said group of resistance elements, and an intermediate terminal positioned to straddle the abutting ends of the respective elements, each of said intermediate terminals having a base partly encircling and gripping the respective ends of two elements acting to mechanically and electrically connect said elements. 30

2. A resistance unit including a resistance element made up of a plurality of sections, said sections abutting, a terminal arranged at each end of said element, and an intermediate terminal arranged to straddle the abutting ends of each of 35 each two sections, said intermediate terminals having a base overlapping the respective ends of two adjacent sections formed with clinching members for clinching the base of said two adjacent sections to permanently provide a mechanical and electrical connection for said sections. 40

3. A resistance unit including a resistance element formed of a plurality of sections, said sections abutting, each of said sections having an insulating base and a winding of resistance wire 45 extending from one end to the other, a terminal arranged at each end of said resistance element and at all said abutting ends, the terminals of the abutting ends having bases clinched around 50 the sides and under surfaces of the respective abutting sections to electrically and mechanically connect said sections together, said clinched terminals pinching the wires at the respective ends of said sections. 55

JOHN J. MUCHER.
